(57) **CLAIM**

The ornamental design for a side turn signal lamp, as shown and described.

DESCRIPTION

FIG. 1 is a perspective view of a first embodiment of my new side turn signal lamp design.

FIG. 2 is a top plan view of a first embodiment of my new side turn signal lamp design.

FIG. 3 is a bottom plan view of a first embodiment of my new side turn signal lamp design.

FIG. 4 is a first side elevational view of a first embodiment of my new side turn signal lamp design.

FIG. 5 is a first end elevational view of a first embodiment of my new side turn signal lamp design.

FIG. 6 is a second side elevational view of a first embodiment of my new side turn signal lamp design.

FIG. 7 is a second end elevational view of a first embodiment of my new side turn signal lamp design.

FIG. 8 is a perspective view of a second embodiment of my new side turn signal lamp design.

FIG. 9 is a top plan view of a second embodiment of my new side turn signal lamp design.

FIG. 10 is a bottom plan view of a second embodiment of my new side turn signal lamp design.

FIG. 11 is a first side elevational view of a second embodiment of my new side turn signal lamp design.

FIG. 12 is a first end elevational view of a second embodiment of my new side turn signal lamp design.

FIG. 13 is a second side elevational view of a second embodiment of my new side turn signal lamp design; and, FIG. 14 is a second end elevational view of a second embodiment of my new side turn signal lamp design.
